(57) **CLAIM**

The ornamental design for an analog scale for measuring pain, as shown and described.

DESCRIPTION

FIG. 1 is a perspective view of an analog scale for measuring pain, showing our new design;

FIG. 2 is a perspective view thereof, opposite that shown in FIG. 1;

FIG. 3 is a plan view of FIG. 2;

FIG. 4 is a plan view of FIG. 1;

FIG. 5 is an end elevational view thereof;

FIG. 6 is a side elevational view thereof;

FIG. 7 is an end elevational view thereof; and,

FIG. 8 is a side elevational view thereof.

The broken lines in the figures are for illustrative purposes only and forms no part of the claimed design.
